UNITED STATES PATENT OFFICE.

GEORGE A. WEBSTER, OF CHICAGO, ILLINOIS.

GAS-HEATER.

1,264,235.

Specification of Letters Patent. Patented Apr. 30, 1918.

Application filed July 24, 1917. Serial No. 182,427.

To all whom it may concern:

Be it known that I, GEORGE A. WEBSTER, a citizen of the United States, and resident of Chicago, county of Cook, and State of Illinois, have invented certain new and useful Improvements in Gas-Heaters, of which the following is a specification and which are illustrated in the accompanying drawings, forming a part thereof.

10 The invention relates to domestic heaters and has particular reference to those heaters which are intended to warm the rooms in which they are located. The invention contemplates a heater which is especially constructed for the use of gas as fuel and is provided with flues which are arranged to effect an efficient transmission of heat to the surrounding air. The object of the invention is to provide an improved heater affording great economy in the use of fuel although of simple and inexpensive construction and having an attractive appearance.

15 In the accompanying drawings, Figure 1 is a perspective view showing the improved heater,

20 Fig. 2 is a central upright transverse sectional view,

25 Fig. 3 is a detail perspective view showing the manner in which certain flues may be connected,

30 Fig. 4 is a central upright longitudinal sectional view, and

35 Fig. 5 is a plan sectional view taken on the line 5—5 of Fig. 4.

40 The improved heater may be constructed principally from sheet metal. It preferably comprises a combustion chamber 10 of substantial proportions and upright chambered end walls 11 and 12. The chambered end walls 11 and 12 are located at the opposite ends of the combustion chamber 10 and they extend a substantial distance above the top of this chamber, as at 13 and 14. These up-

45 wardly projecting portions of the chambered end walls are connected at frequent intervals by two sets of horizontal flues 15 and 16. The use of a considerable number of these flues is permitted without extend-

50 ing the heater to an undue height, by making the several flues of each set relatively broad and shallow, the width of each flue being slightly less than half the width of the heater from front to rear. The flues 15 and 16 are directly exposed to the air of the room throughout their entire length and

provision is also made to permit a circulation of air upwardly between the flues of the two sets. As shown the flues 15 and 16 of the two sets are arranged in front of, and in rear of, the mid-width of the heater respectively, with a relatively narrow intervening air space 17. This air space extends from the top of the combustion chamber 10 upwardly through the heater. To facilitate the circulation of air through the air space 17, an upright air flue 18 extends centrally through the combustion chamber 10. Preferably the air flue 18 is made relatively long and narrow to substantially conform to the horizontal dimensions of the air space 17, but the flue 18 does not extend the full distance between the chambered end walls 11 and 12. As the heater will frequently be located near one of the walls of the room, a tendency to discharge the heated air outwardly away from the wall is obtained by slightly inclining each of the flues 15, 16, from the front toward the rear of the heater.

55 A free admission of air to the lower end of the flue 18 requires that the combustion chamber 10 is to be supported a short distance above the floor. As shown, a base having legs 19 is provided. A convenient construction is provided if the legs 19 are connected in pairs, forming an integral base section 20 at each end. These base sections are rigidly connected by horizontal angle bars 21 and 22, at the front and rear of the heater. Each of the chambered end walls 11 and 12 rests upon one of the base sections 20. As a means for connecting each end wall with the base, the lower end of the inner wall plate of each end wall projects downwardly against the inner face of the corresponding base section, as at 23 (Fig. 4), and is attached thereto by screw bolts 24. The combustion chamber 10 is held in place by providing the inner wall plate of each end wall member with a flange 25 which enters the corresponding end of the combustion chamber. Similarly, the inner wall plate of each end wall member is formed with a flange 26 for entering the adjacent end of each of the flues 15, 16. It follows from this arrangement that the inner wall plates of the chambered end walls 11 and 12 must be assembled with the combustion chamber 10 and flues 15, 16, before the end walls are applied to the base sections 20. Under these circumstances a plurality of tie rods, as 27 and 27^a, are employed for

uniting the inner wall plate of the two end wall members. As shown, the tie rods 27 extend longitudinally through the combustion chamber 10, adjacent the corners of the chamber. The tie rods 27^a extend through the flues 15, 16, preferably near the front and rear margins of these flues respectively. Corner plates 28, engaging the adjacent parts of the corresponding inner wall plates 10 of the end wall members 11 and 12, are applied to the ends of the tie rods 27. Similarly, straps 29 which extend across and beyond the margins of the flues 15 or 16, are applied to the ends of the tie rods 27^a.

15 To permit the assembling of the parts, in the manner just described, the outer wall plate, as 30, of each end wall member 11 and 12 is desirably connected with the corresponding inner wall plate, as 31. As shown, 20 each outer wall plate 30 is formed with a flange 32, at each side, and this flange makes face contact with the corresponding inner wall plate 31 at its margins. Screw bolts, as 33, are then passed through the flanges 32 of 25 each outer wall plate 30 and through the corresponding inner wall plate 31.

Preferably a clamping member 34, designed to give the heater a finished appearance, is employed for connecting the two 30 plates 30 and 31 of each end wall member 11 and 12 at the top. As shown, the clamping member 34 is of angular shape in cross section and extends the full width of the heater. Two bolts 35, one adjacent each 35 end, serves for securing each of the clamping members 34 in place. In addition to providing a secure fastening between the two plates 30 and 31 of the wall members 11 and 12, the clamping members 34 serve to cover 40 the joint between these parts, thereby giving the heater a finished appearance at the top.

The construction contemplates a circulation of the heated products of combustion from the combustion chamber 10 through 45 the several flues 15, 16, of each vertical row in series from the bottom to the top of the heater. For this purpose a series of horizontal partitions 36 is provided in the chamber of each of the end wall members 11 and 50 12. The partitions 36 in one of the end wall members, as 11, serve to divide the corresponding chamber between each alternate pair of flues 15, 16. The partitions 36 in the other end wall member, as 12, serve to divide 55 the corresponding chamber below the lowest flues 15, 16 and between the succeeding pairs of adjacent flues from the bottom to the top of the heater. The products of combustion accordingly pass from the combustion chamber 10 through that part of the chamber of the end wall member 11 which is below the lowest partition 36 in that member, to the lowest flues 15, 16. They then 60 pass horizontally through the succeeding pairs of flues 15, 16 alternately in opposite

directions to the top of the heater. When an even number of flues 15, 16, are provided, as shown, the outer wall plate 30 of the end wall member 11 is formed with a flanged aperture 37, above the highest partition 36, 70 for the attachment thereto of a stove pipe elbow, as 38.

In view of the division of the combustion chamber 10 by the air flue 18 the gas burner, as 39, is preferably constructed to extend 75 upon both sides of this air flue. It has been found that great efficiency is obtained if the gas burner 39 is of U-shape. Under these circumstances the two arms of the U-shaped burner are located within the combustion 80 chamber 10 at opposite sides of the air flue 18, while the end of the burner is located beyond that end of the air flue 18 which is remote from the end wall member, as 11, by which the products of combustion are first 85 received. An ample supply of air for combustion is provided by the formation of a plurality of openings, as 44, in the floor of the combustion chamber 10. To insure that all of the air which enters through these 90 openings will be heated to a high temperature before entering the flues 15, 16, the openings 44 are preferably confined to that part of the floor of the combustion chamber which is adjacent the curved portion of the 95 U-shaped burner 39.

I prefer to form the burner 39 from round pipe with two horizontal rows of apertures 40 extending throughout the length of the same, one row of the said apertures 40 being located just under the widest part of the burner, at each side. A single gas pipe 41 will usually serve for supplying the entire burner 39. This gas supply pipe is controlled by a valve 42 in the usual manner 100 and enters the combustion chamber 10 through one of the openings 40 in the floor of the said chamber. When the burner 39 is of the preferred U-shape the gas pipe 41 connects with the burner at the curved portion of the U. Access to the burner for lighting the same is provided by mounting a door 43 in the front wall plate of the combustion chamber 10. Owing to the continuous extension of the burner apertures 110 throughout the length of both arms of the burner and across its curved portion, access to that arm of the burner which is adjacent the door 43, for lighting the same, is sufficient.

The length and number of the flues 15, 16 and the provision which is made for an efficient circulation of air about these flues, insures that substantially all of the heat which is generated by the combustion of 115 gas in the combustion chamber 10 is transmitted to the room before the products of combustion enter the stove pipe elbow 38. An economical use of the fuel is thereby obtained and the room to be heated may be 120 125 130

brought to the desired temperature within a short time after the burner, as 39, is lighted.

I claim as my invention:

- 5 1. In a gas heater, in combination, an oblong rectangular combustion chamber having a longitudinally disposed relatively long and narrow vertical air flue extending centrally through the same, chambered walls rising from and communicating with the ends of the combustion chamber, and two vertical series of relatively broad and shallow transversely inclined exposed flues extending horizontally between the said chambered walls above the combustion chamber, the flues of each series being only slightly less than half the width of the said chambered walls and the two series of flues being respectively located in front and in rear of the longitudinal median plane of the heater with an intervening air space. 45
- 10 2. In a gas heater, in combination, a combustion chamber having a vertical air flue extending through the same, chambered walls rising from and communicating with the ends of the combustion chamber, and a group of exposed flues separated to permit the circulation of air between the several flues of the group extending horizontally between the said chambered walls above the combustion chamber. 50
- 15 3. In a gas heater, in combination, an oblong rectangular combustion chamber having a longitudinally disposed relatively long and narrow vertical air flue extending centrally through the same, chambered walls rising from and communicating with the ends of the combustion chamber, two vertical series of relatively broad and shallow exposed flues extending horizontally between the said chambered walls above the combustion chamber, the flues of each series being only slightly less than half the width of the said chambered walls and the two series of flues being respectively located in front and in rear of the longitudinal median plane of the heater with an intervening air space. 55
- 20 4. In a gas heater, in combination, a combustion chamber having a vertical air flue extending through the same, chambered walls rising from and communicating with the ends of the combustion chamber, and a group of exposed flues separated to permit the circulation of air between the several flues of the group extending horizontally between the said chambered walls above the combustion chamber. 60
- 25 5. In a gas heater, in combination, an oblong rectangular combustion chamber having a longitudinally disposed relatively long and narrow vertical air flue of less length than the combustion chamber and extending centrally through the same, chambered walls rising from and communicating with the ends of the combustion chamber, a group of exposed flues extending horizontally between the said chambered walls above the combustion chamber and a U-shaped gas burner extending within the combustion chamber and on each side of and across one end of the said vertical air flue. 65
- 30 6. In a heater, in combination, an oblong rectangular combustion chamber having a longitudinally disposed relatively long and narrow vertical air flue of less length than the combustion chamber and extending centrally through the same, chambered walls rising from and communicating with the ends of the combustion chamber, two vertical series of relatively broad and shallow exposed flues extending horizontally between the said chambered walls above the combustion chamber, the flues of each series being only slightly less than half the width of the said chambered walls and the two series of flues being respectively located in front and in rear of the longitudinal median plane of the heater with an intervening air space, and a gas burner mounted within the combustion chamber. 70
- 35 7. In a heater, in combination, an oblong rectangular combustion chamber having a longitudinally disposed relatively long and narrow vertical air flue of less length than the combustion chamber and extending centrally through the same, chambered walls rising from and communicating with the ends of the combustion chamber, two vertical series of relatively broad and shallow exposed flues extending horizontally between the said chambered walls above the combustion chamber, the flues of each series being only slightly less than half the width of the said chambered walls and the two series of flues being respectively located in front and in rear of the longitudinal median plane of the heater with an intervening air space, and a gas burner mounted within the combustion chamber. 75
- 40 8. In a heater, in combination, an oblong rectangular combustion chamber having a longitudinally disposed relatively long and narrow vertical air flue of less length than the combustion chamber and extending centrally through the same, chambered walls rising from and communicating with the ends of the combustion chamber, two vertical series of relatively broad and shallow exposed flues extending horizontally between the said chambered walls above the combustion chamber, the flues of each series being only slightly less than half the width of the said chambered walls and the two series of flues being respectively located in front and in rear of the longitudinal median plane of the heater with an intervening air space, and a gas burner mounted within the combustion chamber. 80
- 45 9. In a heater, in combination, an oblong rectangular combustion chamber having a longitudinally disposed relatively long and narrow vertical air flue of less length than the combustion chamber and extending centrally through the same, chambered walls rising from and communicating with the ends of the combustion chamber, two vertical series of relatively broad and shallow exposed flues extending horizontally between the said chambered walls above the combustion chamber, the flues of each series being only slightly less than half the width of the said chambered walls and the two series of flues being respectively located in front and in rear of the longitudinal median plane of the heater with an intervening air space, and a gas burner mounted within the combustion chamber. 85
- 50 10. In a heater, in combination, an oblong rectangular combustion chamber having a longitudinally disposed relatively long and narrow vertical air flue of less length than the combustion chamber and extending centrally through the same, chambered walls rising from and communicating with the ends of the combustion chamber, two vertical series of relatively broad and shallow exposed flues extending horizontally between the said chambered walls above the combustion chamber, the flues of each series being only slightly less than half the width of the said chambered walls and the two series of flues being respectively located in front and in rear of the longitudinal median plane of the heater with an intervening air space, and a gas burner mounted within the combustion chamber. 90
- 55 11. In a heater, in combination, an oblong rectangular combustion chamber having a longitudinally disposed relatively long and narrow vertical air flue of less length than the combustion chamber and extending centrally through the same, chambered walls rising from and communicating with the ends of the combustion chamber, two vertical series of relatively broad and shallow exposed flues extending horizontally between the said chambered walls above the combustion chamber, the flues of each series being only slightly less than half the width of the said chambered walls and the two series of flues being respectively located in front and in rear of the longitudinal median plane of the heater with an intervening air space, and a gas burner mounted within the combustion chamber. 95
- 60 12. In a heater, in combination, an oblong rectangular combustion chamber having a longitudinally disposed relatively long and narrow vertical air flue of less length than the combustion chamber and extending centrally through the same, chambered walls rising from and communicating with the ends of the combustion chamber, two vertical series of relatively broad and shallow exposed flues extending horizontally between the said chambered walls above the combustion chamber, the flues of each series being only slightly less than half the width of the said chambered walls and the two series of flues being respectively located in front and in rear of the longitudinal median plane of the heater with an intervening air space, and a gas burner mounted within the combustion chamber. 100
